UNITED STATES PATENT OFFICE

HIRAM B. CANNON, OF ERIE, PENNSYLVANIA

APPARATUS FOR HEATING FLUIDS

Application filed January 31, 1927. Serial No. 164,668.

This invention relates to an apparatus for heating fluids, the embodiment of the apparatus shown and described herein being a steam-boiler installation.

5 It is the general purpose and object of the invention to provide an apparatus of the character referred to which will utilize a high percentage of the heat units liberated by the combustion of the fuel; which will secure a 10 high rate of combustion of the fuel; and which will secure perfect combustion of the fuel, without injury to the furnace walls and the tubes or other fluid container. A further object of the invention is to provide an apparatus 15 which will enable a very considerable proportion of the boiler surface to be heated by radiation from the outer wall of a combustion chamber surrounded by such boiler surface and wherein a considerable proportion 20 of the radiant heat from the combustion within such wall will be transferred to the said surface. A still further object of the invention is to provide a novel and cooperating construction of boiler and boiler furnace 25 whereby maximum efficiency is obtained.

Still further, and more limited objects of the invention will appear hereinafter and will be realized in and through the various features of construction illustrated in the 30 drawings and by the combinations of elements and steps embodied in the claims.

The apparatus shown herein will be referred to generally as a boiler, which term will include both the steam generator and the 35 cooperating furnace construction.

Referring to the drawings, Figs. 1 and 1^a represent a central vertical sectional view through a steam-boiler constructed in accordance with my invention, certain parts being 40 shown in elevation; Figs. 2, 3 and 4 are details in transverse section corresponding respectively to the lines 2—2, 3—3 and 4—4 of Fig. 1; Fig. 5 is a detail in vertical section of the lower portion of the boiler, showing a modification of the means for supplying water to the lower ends of the vertical series of boiler tubes; Fig. 6 is an enlarged sectional detail corresponding to part of the line 6—6 of Fig. 3; Fig. 7 a sectional detail corresponding to the line 7—7 of Fig. 6; Fig. 8 a detail in section

corresponding to the line 8—8 of Fig. 7; Fig. 9 a side elevation of one of the blocks for supporting the combustion chamber from the boiler tubes; Fig. 9^a a plan view of one of said blocks; Fig. 10 a side elevation of one 55 of the blocks or bricks of which the wall of the combustion chamber is composed; Fig. 11 a view, similar to Fig. 8, showing a modification; and Figs. 12 and 13 are cross-sectional views showing modified forms of my 60 combustion chamber.

Describing the various parts by reference characters, 1 denotes upright members, shown as I-beams and which support at their upper ends transverse members 2 also shown as I-beams. The members 1 and 2 are so arranged that the members 2 form a rectangular horizontal support for the bottom of the boiler casing of the furnace and the parts thereabove, it being noted, by reference to Fig. 3, 70 that the ends of one pair of such members 2 extend beyond the said casing and the parts thereabove while the ends of the other pair preferably do not extend beyond the casing.

3 denotes the base of the boiler casing and the 75 hearth or bottom for the combustion chamber. This base is made of suitable refractory material having high heat-and-slag resistance and low heat-conductivity. Magnesite or like material is suitable for this purpose. The 80 base is provided with a shoulder 3^a on its under surface by means of which it is supported on the beams 2 and is provided with an extension 4, within such beams, providing an ash pit, said pit being encased with heat-insulating material 4^a and a metal shell 4^b. Extending upwardly from the outer edge of the base 3 is a boiler casing 5, which casing is preferably made of material having low heat conductivity and high heat-reflecting properties, 85 silicof or Infrax being examples of such material. On top of the casing is a stack 6.

7 denotes a combustion chamber which is located within and spaced from the lower part of the casing, with its lower end supported 90 on the base 3. The outer wall or walls of this combustion chamber should be composed, in part at least, of refractory material having high heat-radiating capacity at high temperatures, the best material for this purpose be- 100

ing silicon carbide. In the form of the invention shown in Figs. 1-11 inclusive, it is contemplated that the entire wall or walls of the combustion chamber shall be composed of material having the qualities referred to. The said refractory material is made in the form of blocks, indicated generally at 8 and provided with interlocking tongues and grooves, as will appear hereinafter. At its upper end, the top of the combustion chamber 7 is provided with a shoulder 9 which engages the inner wall of the casing 5, the upper end of the combustion chamber being preferably beveled outwardly and upwardly as shown at 15 7^a.

The casing 5 and the combustion chamber 7 are preferably square in section, providing spaces between the sides thereof for the tubes of the boiler proper, which will now be described.

10 denotes a water-and-steam drum which is supported outside of and near the top of the casing 5. From the bottom of this drum, pipes 11, 12, 13 and 14 connect the bottom of the said drum with headers 15, 16, 17 and 18, respectively (see Fig. 4), the said headers being located below the shoulder 3^a and each being located below one of the four spaces A provided between the side walls of the combustion chamber and the inner walls of the casing. From each of the headers 15, 16, 17 and 18, a series of vertical tubes 15^a, 16^a, 17^a and 18^a, respectively, extends upwardly through the spaces A thereabove, in proximity to but out of contact with the outer walls of the combustion chamber adjacent thereto, and through the shoulder 9 and in proximity to the inner sides of the casing 5. The tubes 15^a of one series are connected at their upper ends to the drum 10; while the tubes in the other series are connected at their upper ends to headers or drums 16^b, 17^b and 18^b, respectively. The drums or headers 16^b and 18^b are connected to the drum 10 by short connections 16^c and 18^c respectively, while the drum or header 17^b is connected to the drum 10 by means of an upper and a lower series of tubes 19, 19^a which extend upwardly from said drum or header across the casing 5.

20 denotes a header which is connected with the top of the drum 10 by a connection 21 and from which header vertical coils 22 of a superheater extend through and across the casing 5, above the tubes 19, 19^a, the lower ends of the superheater tubes being connected with a header 23 from which a delivery pipe 24 extends.

In the stack 6, above the superheater coil, is an air heater, indicated generally at 25, the said heater being provided with a supply duct 26 and a delivery duct 27 extending downwardly to a bustle pipe 28 which extends about the casing 5, above the lower end thereof. From this pipe there depend four supply pipes 29 from each of which in turn a short

pipe 30 projects inwardly toward a corner of the casing 5. The pipes 30 are for the purpose of supplying secondary preheated air for the combustion of the mixture of fuel and primary air supplied to the burners, indicated generally at B. Each burner is supplied with such mixture of fuel and primary air through vertical pipes 31 extending into the T 32 which supports the burner proper. With the embodiment of my invention as shown herein, it is contemplated that the burners shall be supplied with pulverized fuel, and the pipes 31 are for the purpose of conducting air, or like combustible fluid under pressure, together with the powdered fuel suspended therein, to the respective burners, this mixture of fuel and air being further mixed with the hot air delivered through the pipes 29 and 30.

It will be noted, from Figs. 1^a and 3, that the burners are generally triangular or fan shaped, each being provided with an elongated discharge slot B', the said slots being arranged vertically and the burners projecting through the corner portions of the casing 5 and of the combustion chamber 7, but with their axes slightly out of coincidence with diagonals connecting such corners. This arrangement is shown in Fig. 3, wherein it will be seen that the inner wall B² of the mixture discharged by each burner into the combustion chamber is approximately in a vertical plane connecting the diagonally opposite corners of the combustion chamber, while the outer wall B³ of such mixture diverges from such plane. The result of this arrangement is that the fuel mixtures delivered by the four burners will impinge close to the center of the combustion chamber, producing a vortex action about the vertical axis of the said chamber. The purpose of this arrangement of the burners or nozzles is to enable a quick and complete admixture of the air and powdered fuel and a quick and complete combustion of such mixture to be obtained entirely within the combustion chamber when the wall or walls thereof are at a high temperature. This quick and complete combustion not only enables me to burn a very large quantity of fuel in proportion to the size of the combustion chamber, but to burn the same completely and without injury to the wall of the combustion chamber, while enabling the latter to be raised quickly to and maintained at the temperature which will insure the maximum transfer of heat by radiation therefrom to the series of tubes 15^a-18^a which surround the walls of said chamber.

The combustion chamber 7 is comparatively short, it having been found that, due to the manner of burning the fuel therein, this fuel is completely consumed by the time it has reached the top of said chamber.

In actual operation, the combustible streams, from the moment when they leave

the burners until they reach the center of the vortex, are indicated by dazzling white, horizontally expanding, vertical bands of flame. There is little other evidence of flame within the zone extending from the bottom to the top of the burner openings, as above described. Furthermore, the combustion reaction above the top plane of the burners is practically transparent. This transparent condition of the combustion zone enables me to obtain a maximum transfer of radiant heat therefrom through the walls of the combustion chamber to the tubes 15^a—18^a adjacent thereto, and directly to exposed portions of the tubes 15^a—18^a above the combustion zone as well as directly to the inclined tubes 19—19^a and, through re-radiation, from the inside of the walls 7 to the exposed tubes 15^a—18^a, 19, 19^a above the combustion zone. This transfer of radiant energy occurs not only from the outer boundaries of the combustion zone, but throughout its entire extent, due to the combustion reactions occurring therein.

Because of the high temperature at which the walls of the combustion chamber are maintained, radiant heat reflected from and re-radiated by the inner surfaces of the walls assists in securing early ignition of the combustible mixture delivered by the burner nozzles and an early reduction of the solid carbon constituents of such mixture to gaseous combinations thereof, which gaseous combinations are completely reduced by the hot zone provided by the said chamber, even though the chamber is comparatively short.

The tubes 15^a—18^a, being spaced from the walls of the casing 5, are not cooled on their outer sides by such walls and, being spaced from the walls 7, their inner sides do not tend to cool such walls and increase the resistance of the latter to the transfer of radiant heat to the said tubes, as would be the case were the disposition of the walls and tubes somewhat intimate or merged. The casing 5, being made of heat-reflecting, as well as heat-insulating, material, assists materially in the heating of the tubes by reflecting against the outer surfaces thereof the heat received by radiation from the combustion chamber 7.

The steam generated in the tubes 15^a—18^a is delivered to the drum 10, it being noted that the tubes 19^a extend across the top of the casing, whereby the fluid passing therethrough will be subjected, not only directly to radiant heat from the inner surfaces of the walls 7, but to the sensible heat of the burned gases impinging thereon and passing therebetween. As the products of combustion continue to rise, they pass in contact with the superheater coils 22 and thence to the air heater 25.

Reference has been made hereinbefore to the ability of the furnace part of my invention to secure a very high rate of combustion

without injury to the radiating screen formed by the wall or walls 7 of the combustion chamber and to secure the transfer of a considerable proportion of the heat units developed by such combustion to the tubes 15^a—18^a by radiation from said screen, and to accomplish this result without elevating the temperatures of the wall or walls 7 to a destructive point. The height and cross sectional area of the combustion chamber are so designed with reference to the type of burners employed and the rate of combustion of the mixture delivered thereby as to secure these results. For instance, I have found that I can operate my boiler and furnace unit at a combustion speed ranging from 180,000 to 375,000 B. t. u.'s released per cubic foot of combustion space per hour, these figures being based on the space enclosed by the combustion chamber. At the same time, the B. t. u. absorption per square-foot of boiler absorbing surface may be as much as 100,000 or more per hour, especially in the tubes 19, 19^a and those surfaces of the tubes 15—18^a which are exposed directly to the combustion volume, such absorption being dependent upon the means used to provide positive circulation of the boiler fluid. Provided that the upper limit of combustion speed is not exceeded, the wall or walls 7 will not be destroyed through slagging action. The radiating screen constituted by the wall or walls 7 is used primarily to maintain the combustion zone at a very high temperature, so that the combustible matter discharged thereinto by the burners may be very quickly and completely consumed. The screen also protects the boiler tubes adjacent this combustion zone from destruction by direct contact with the flames within the said screen. The general arrangement of the burner nozzles is also important in securing the kind of combustion within the wall or walls 7 that will enable the high rate of combustion and the high percentage of heat transfer to the tubes to be effected. By directing the streams from the burners as closely to the axis C as indicated, I am enabled to limit the luminous or opaque condition of the combustion reaction to a zone which does not extend materially above the plane of the tops of the burner; and this arrangement not only enables me to burn completely a large quantity of fuel, as pointed out hereinbefore, but enables me to do so without subjecting the walls of the combustion chamber to destructive slag and flame reactions, as well as localized high temperatures. Wherever the material of which the wall or walls 7 is composed is subjected to oxidation, such oxidation may be prevented by circulating products of combustion through the vertical spaces A between the said walls and the casing 5. To accomplish this purpose a pipe 33 is connected with the stack above the air heater, with its lower

end connected with a blower 34 which delivers the said products to a bustle pipe 35 surrounding the casing 5 and the lower end of the combustion chamber and delivering such products into the bottoms of the spaces A through connections or tuyères 36. The flanges or shoulders 9 are provided with slots 9^a permitting the circulation of the products through the spaces A.

10 When operating at an excessive rating, it is desirable to employ positive means for forcing the liquid from the drum 10 into the bottoms of the tubes 15^a—18^a. An arrangement for accomplishing this purpose is shown in Fig. 5, wherein one of the down pipes from the drum 10 is shown as provided at the lower inwardly-deflected end thereof with a pump, which may be of the turbine type and which is indicated conventionally at 37, the pump shaft 38 being driven by a motor 39. In this view only one of the pipes is shown, the pipe being designated 11^a and communicating at its lower end with a drum or header 15. This arrangement insures a positive and forced circulation of the liquid from the drum 10 to the various lower headers and upwardly into and through the tubes 15^a—19^a thereabove, which circulation will prevent blistering of the said tubes, the arrangement insuring the presence of the liquid, as such, in the tubes 15^a—18^a.

15 In Fig. 12 there is shown a modification of my invention wherein only two opposed walls 7 of the combustion chamber are of silicon carbide. The other two walls are composite walls, each consisting of an inner facing 7^a of refractory material and a metal backing 7^b, to which the tubes 16^a and 18^a are clamped, as shown at 7^c. The composite walls are preferably made up of blocks.

20 In Fig. 13 there is shown a further modification of the invention wherein two opposed walls 7 are of silicon carbide, the other two opposed walls being formed by the tubes 16^a and 18^a, which tubes are provided with fins 16^b and 18^b, respectively, the fins on the casting tubes meeting and enabling the tubes and fins on each side to constitute a wall, as before stated. In both Figs. 12 and 13, the outer surfaces of the tubes 16^a and 18^a are shown as in substantial contact with the inner wall of the outer casing.

25 In all forms of my invention, at least two opposite walls of the combustion chamber are formed of a material having high heat-radiating capacity at high temperatures and serving to heat by radiation tubes outside and spaced therefrom. This enables sufficient sensible heat to be stored to maintain an adequate amount of heat in the furnace for burning the fuel.

30 The combustion chamber, as pointed out hereinbefore, will function with maximum efficiency where the wall or walls thereof are

made principally of silicon carbide. In practice, where such material is used, the walls of the chamber are built up from a plurality of blocks 8 united by inter-engaging tongues and grooves. In the drawing (see Figs. 6 and 10) each such block is shown as provided with a tongue 8^a on the upper face thereof and a corresponding groove 8^b on the lower face thereof, the said tongues and grooves extending in the direction of the length of the wall of which the blocks form a part. In addition, each block 8 is provided with a tongue 8^c at one end thereof and a groove 8^d at the other end thereof. The tongues 8^c and grooves 8^d extend vertically in the wall of which they form a part. To stabilize the walls of the combustion chamber, they are tied or anchored to pairs of tubes in the series 15^a—18^a, as shown in Figs. 3 and 6—11 inclusive, each side wall of the combustion chamber being provided with outwardly extending anchoring header walls, indicated generally at D, which will be described in detail.

35 Each wall D consists of a vertical series of header blocks 40, each of the said blocks being preferably silicon carbide and being conveniently of twice the height of the blocks or tiles 8. Each block 40 is provided with a pair of tongues 40^a, 40^b extending across the top thereof and a pair of grooves 40^c, 40^d extending across the bottom thereof. In addition, a vertical groove 41 in one face of the block connects the ends of the tongue 40^b and groove 40^d adjacent such face; and a tongue 41^a on the opposite face of said block connects the ends of the tongue 40^b and groove 40^d adjacent to such face. This construction affords an effective means for interlocking the header blocks 40 with the blocks 8 and with the walls 7 composed of such blocks. By inserting the right-hand end of each block 40 between the opposed ends of two pairs of blocks 8, the blocks 40 will be interlocked with the blocks 8 by the engagement of the tongues 8^c with the grooves 41 and by the engagement of the tongue 41^a with the grooves 8^b; while the blocks 40 will be interlocked with each other by means of the tongues 40^a, 40^b and the grooves 40^c, 40^d.

40 In order to secure the header walls D, formed by the blocks 40, to the pipes, I have provided two forms of connection, that shown in Figs. 6—8, and that shown in Fig. 11. In Figs. 6—8, each pipe to which a wall D is to be connected is provided with vertically spaced lugs 15^a, the lugs being preferably welded to the pipes, each lug having a vertical slot 15^b therethrough, which slot receives the reduced threaded end of a stud 42, the stud being secured to the lug by means of a nut 43 on such threaded end. The opposite end of each stud is adapted to enter a diagonal shallow slot 44 provided therefor in one of the blocks 40. This ar-

5 arrangement enables the studs to be assembled readily with reference to the lugs 15^a and the header blocks should the said blocks be somewhat out of alignment and at the same time enables the studs to be adjusted to final 70 position with their upper faces engaging the upper inclined surfaces of the slots 44, whereby they will sustain the outer or projecting ends of the blocks. It will be noted

10 that the lugs 15^a and the studs 42 are staggered on the pipes comprising each pair, one pipe 15^a being connected to half of the blocks 40 while the other pipe is connected to the other half of the blocks 40 in the common 15 wall D.

15 In Fig. 11 there is shown a modification wherein each of the blocks 40 is supported from a pipe (such as 15^a) by means of studs 45 each of which is carried by a clamp 46 20 which extends about a portion of the pipe by which the stud is supported, each stud being provided with a screw 47 threaded therethrough and adapted to engage the adjacent surface of the tube. The end of each 25 clamp 46 is spaced less than 180 degrees from the end of the screw 47 so that, when the screws are set up, the clamps will be forced against their respective pipes and will each afford an adequate support for the 30 stud carried thereby. The combustion chamber is further stabilized by the shoulder 9 which engages the casing 5 and by the pipes 15^a—18^a extending through said shoulder.

35 The boiler installation described herein is particularly efficient for use with pulverized fuel and makes effective use of the radiating effect of the incandescent ash upon the exposed portions of the tubes 15^a—18^a, this 40 effect being materially greater on these tubes than on the top bank of tubes 19, 19^a. This enables me to cool the ash far below the temperature at which it becomes molten, by the 45 time it reaches the tubes 19, 19^a, thereby preventing the glazing or the forming of a solid deposition of ash on such tubes. Consequently, the side wall tubes 15^a—18^a as 50 exposed serve the above purpose as well as absorb re-radiation from the inner surface 55 of the screen or wall 7 and also direct radiations from combustion reactions throughout the combustion zone; and it is proper to state that these exposed tubes prevent the blistering or destruction of the top bank of tubes 19, 19^a.

In operating with pulverized fuel, the matter of removing the slag is important. The arrangement of the burners B produces (as stated hereinbefore) an opaque flame 60 above the hearth or base 3, and this flame protects the hearth or base against concentrated heat radiation from within the flame as well as from the transparent combustion zone thereabove, and thus avoids heating the 65 hearth or base to the critical temperature at which the molten slag would react with the hearth or base to destroy the latter. This molten slag will flow down the inclined top of the base and will be delivered through the central opening therein into a car 48 in the pit therebelow, the car, when filled, being removed through a suitable door 49. 70

Having thus described my invention, what I claim is:

1. In a boiler, the combination of a vertically extending casing composed of heat-resistant and heat-reflecting material, a combustion chamber located in the lower portion of the said casing and spaced therefrom and arranged to discharge into the 75 portion of the said casing thereabove, the said combustion chamber being composed principally of material having high heat-radiating qualities at high temperatures, headers beneath the space provided between 80 the casing and the combustion chamber, a steam and water drum arranged above and beyond the top of the combustion chamber, downcomer tubes connecting the said drum with each of said headers, a vertical series 85 of tubes extending upwardly from each header through the space between the casing and the combustion chamber and along the inner wall of the casing above and beyond such chamber and having their upper 90 ends connected to said drum, one such series of tubes extending across the casing above the combustion chamber, and means for delivering a fuel mixture to the lower portion 95 of said combustion chamber and for 100 burning the mixture within the said chamber.

2. In a boiler, the combination of a vertically extending casing polygonal in section and composed of heat-resistant and heat-reflecting material, a combustion chamber also polygonal in cross section and located in the lower portion of the said casing and spaced therefrom and arranged to discharge 105 into the portion of the said casing thereabove, the said combustion chamber being composed principally of material having high heat-radiating qualities at high temperatures, a header beneath the space provided between each wall of the casing and each wall of the combustion chamber, a steam and water drum arranged above and beyond the top of the combustion chamber, downcomer tubes connecting the said drum 110 with each of said headers, a vertical series of tubes extending upwardly from each header through the space between the casing and the combustion chamber and along the inner wall of the casing above and beyond such chamber, the tubes of one such series having 115 their upper ends connected directly to said drum, headers with which the upper ends of the tubes of the other series are respectively connected, connections between such headers and said drum, one of said connections 120

- comprising tubes extending across said casing, and means for delivering a mixture of pulverized fuel and a combustion-supporting agent to the lower portion of said combustion chamber for burning the mixture within said chamber. 5
3. The combination, with a combustion chamber wall, of spaced fluid-conducting tubes arranged adjacent to the said combustion chamber, header blocks keyed into and projecting outwardly from the said combustion chamber between pairs of said tubes, and means adjustably connecting the header blocks to the tubes of each pair thereby to 10 stabilize the said combustion chamber, the said means comprising studs adjustably secured to said tubes and each having an end entering an inclined slot in the face of the header block adjacent thereto. 15
4. A combustion chamber wall for a fluid heater embodying spaced tubes adapted to extend in proximity to said wall, the said wall comprising a plurality of interlocking blocks, header blocks interposed between blocks of said wall and interlocked therewith and with each other, and means securing said header blocks to said tubes thereby to stabilize the said wall. 20
5. In a boiler, the combination of a vertical combustion chamber composed principally of refractory material having high heat-radiating capacity at high temperatures, a vertical casing surrounding the said combustion chamber and spaced therefrom and extending therebeyond, vertically extending boiler tubes in the space between said chamber and casing and each having a portion thereof extending above and beyond said chamber and into the path of the products of combustion 30 discharged from said chamber, and means for supplying a combustible mixture to said combustion chamber and for completing the combustion of said mixture within the said chamber whereby the flame of combustion is kept out of contact with the tubes in the zone of most intense combustion and the said tubes are heated by radiation from said combustion chamber in such zone as well as by the sensible heat of the products of combustion 35 in the zone beyond the combustion chamber. 40
6. In a boiler, the combination of a vertical combustion chamber composed principally of refractory material having high heat-radiating capacity at high temperatures, a vertical casing surrounding the said combustion chamber and spaced therefrom and extending therebeyond, vertically extending boiler tubes in the space between said chamber and casing and each having a portion thereof extending 50 above and beyond said chamber and into the path of the products of combustion discharged from said chamber, means for supplying a combustible mixture to said combustion chamber and for completing the combustion of said mixture within the said chamber whereby the flame of combustion is kept out of contact with the tubes in the zone of most intense combustion and the said tubes are heated by radiation from said combustion chamber in such zone as well as by the sensible heat of the products of combustion 55 in the zone beyond the combustion chamber, spaced means for supporting the combustion chamber from the said tubes, and means for positively circulating liquid upwardly through the said tubes. 60
7. In a boiler, the combination of a vertical casing, a combustion chamber within the 65
8. In a boiler, the combination of a vertical combustion chamber composed principally of refractory material having high heat-radiating capacity at high temperatures, a vertical casing surrounding the said combustion chamber and spaced therefrom and extending therebeyond, vertically extending tubes in the space between said chamber and casing and each having a portion thereof extending above and beyond the said chamber and into the path of the products of combustion discharged from said chamber, means for supplying a combustible mixture to said combustion chamber and for completing the combustion of said mixture within the said chamber whereby the flame of combustion is kept out of contact with the tubes in the zone of most intense combustion and the said tubes are heated by radiation from said combustion chamber in such zone as well as by the sensible heat of the products of combustion 70 in the zone beyond the combustion chamber, 75
9. In a boiler, the combination of a vertical combustion chamber composed principally of refractory material having high heat-radiating capacity at high temperatures, a vertical casing surrounding the said combustion chamber and spaced therefrom and extending therebeyond, vertically extending tubes in the space between said chamber and casing and each having a portion thereof extending above and beyond the said chamber and into the path of the products of combustion discharged from said chamber, means for supplying a combustible mixture to said combustion chamber and for completing the combustion of said mixture within the said chamber whereby the flame of combustion is kept out of contact with the tubes in the zone of most intense combustion and the said tubes are heated by radiation from said combustion chamber in such zone as well as by the sensible heat of the products of combustion 80 in the zone beyond the combustion chamber, 85
10. In a boiler, the combination of a vertical combustion chamber composed principally of refractory material having high heat-radiating capacity at high temperatures, a vertical casing surrounding the said combustion chamber and spaced therefrom and extending therebeyond, vertically extending tubes in the space between said chamber and casing and each having a portion thereof extending above and beyond the said chamber and into the path of the products of combustion discharged from said chamber, means for supplying a combustible mixture to said combustion chamber and for completing the combustion of said mixture within the said chamber whereby the flame of combustion is kept out of contact with the tubes in the zone of most intense combustion and the said tubes are heated by radiation from said combustion chamber in such zone as well as by the sensible heat of the products of combustion 90 in the zone beyond the combustion chamber, 95
11. In a boiler, the combination of a vertical combustion chamber composed principally of refractory material having high heat-radiating capacity at high temperatures, a vertical casing surrounding the said combustion chamber and spaced therefrom and extending therebeyond, vertically extending tubes in the space between said chamber and casing and each having a portion thereof extending above and beyond the said chamber and into the path of the products of combustion discharged from said chamber, means for supplying a combustible mixture to said combustion chamber and for completing the combustion of said mixture within the said chamber whereby the flame of combustion is kept out of contact with the tubes in the zone of most intense combustion and the said tubes are heated by radiation from said combustion chamber in such zone as well as by the sensible heat of the products of combustion 100 in the zone beyond the combustion chamber, 105
12. In a boiler, the combination of a vertical combustion chamber composed principally of refractory material having high heat-radiating capacity at high temperatures, a vertical casing surrounding the said combustion chamber and spaced therefrom and extending therebeyond, vertically extending tubes in the space between said chamber and casing and each having a portion thereof extending above and beyond the said chamber and into the path of the products of combustion discharged from said chamber, means for supplying a combustible mixture to said combustion chamber and for completing the combustion of said mixture within the said chamber whereby the flame of combustion is kept out of contact with the tubes in the zone of most intense combustion and the said tubes are heated by radiation from said combustion chamber in such zone as well as by the sensible heat of the products of combustion 110 in the zone beyond the combustion chamber, 115
13. In a boiler, the combination of a vertical combustion chamber composed principally of refractory material having high heat-radiating capacity at high temperatures, a vertical casing surrounding the said combustion chamber and spaced therefrom and extending therebeyond, vertically extending tubes in the space between said chamber and casing and each having a portion thereof extending above and beyond the said chamber and into the path of the products of combustion discharged from said chamber, means for supplying a combustible mixture to said combustion chamber and for completing the combustion of said mixture within the said chamber whereby the flame of combustion is kept out of contact with the tubes in the zone of most intense combustion and the said tubes are heated by radiation from said combustion chamber in such zone as well as by the sensible heat of the products of combustion 120 in the zone beyond the combustion chamber, 125

- lower end of the casing and spaced therefrom, the said combustion chamber being composed principally of material having high heat-radiating capacity at high temperatures, boiler tubes extending upwardly through the space between the combustion chamber and the casing and along the inner wall of the casing beyond the said combustion chamber, means for supplying a mixture of pulverized fuel and a combustion-supporting agent to the combustion chamber and for substantially completing the combustion of the mixture within the said chamber, and additional boiler tubes extending transversely of the casing above the upper end of the combustion chamber and spaced therefrom a sufficient distance to enable the ash produced by the combustion of the fuel to be cooled below coalescence by the exposed portions of the first mentioned tubes before the ash reaches the second group of tubes.
10. In a boiler, the combination of a vertical casing, a combustion chamber within the lower portion only of the casing and spaced therefrom, the said combustion chamber being composed principally of material having high heat-radiating capacity at high temperatures, boiler tubes extending upwardly through the space between the combustion chamber and the casing and along the inner wall of the casing beyond the said combustion chamber, means for supplying a mixture of pulverized fuel and a combustion-supporting agent to the combustion chamber and for substantially completing the combustion of the mixture within the said chamber, and additional boiler tubes extending transversely of the casing above the upper end of the combustion chamber and spaced therefrom a sufficient distance to enable the ash produced by the combustion of the fuel to be cooled below coalescence by the exposed portions of the first mentioned tubes before the ash reaches the second group of tubes, and means for positively circulating liquid vertically through the first mentioned tubes.
11. In a boiler, the combination of a vertical casing, a combustion chamber in the lower portion of said casing and spaced therefrom, the said combustion chamber being composed principally of refractory material having high heat-radiating capacity at high temperatures, an elevated steam and water drum located above and beyond the upper end of the combustion chamber, boiler tubes extending upwardly through the space between the said combustion chamber and into the casing above and beyond the said combustion chamber and communicating at their upper ends with said drum, means for supplying a combustible mixture to the said combustion chamber and for substantially completing the combustion of the said mixture in the said chamber, connections for supplying liquid from the said drum to the bot-
- toms of said tubes, and means for producing a forced circulation of such liquid upwardly through the said tubes and into said drum.
12. In a boiler, the combination of a vertical casing, a combustion chamber within and at one end of the casing and spaced therefrom, the said combustion chamber being composed principally of material having high heat-radiating capacity at high temperatures, boiler tubes extending upwardly through the space between the combustion chamber and the casing and along the inner wall of the casing above and beyond the said combustion chamber, additional boiler tubes extending transversely of the casing above and beyond the upper end of the combustion chamber, means for supplying a mixture of pulverized fuel and a combustion-supporting agent to the combustion chamber and for substantially completing the combustion of the mixture within the said chamber, means for producing a forced circulation of liquid upwardly through said tubes, and spaced anchoring means for supporting the combustion chamber from the said tubes.
13. In a boiler, the combination of a vertical casing, a combustion chamber within and at one end of the casing and spaced therefrom, the said combustion chamber being composed principally of material having high heat-radiating capacity at high temperatures, boiler tubes extending upwardly through the space between the combustion chamber and into the casing beyond the said chamber, additional boiler tubes extending transversely of the casing adjacent to the upper ends of the former tubes, means for supplying a mixture of pulverized fuel and a combustion supporting agent to the combustion chamber and for substantially completing the combustion of the mixture within the said chamber, means for producing a forced circulation of liquid upwardly through said tubes, means for withdrawing a limited proportion of the products of combustion from a zone beyond the upper ends of said tubes and for circulating the same through the space between the casing and the combustion chamber thereby to prevent oxidizing of the said chamber, and spaced means for supporting the chamber from the first mentioned tubes.
- In testimony whereof, I hereunto affix my signature.
- HIRAM B. CANNON.
